Primary Examiner — Michael C Stout*Assistant Examiner* — Fitzgerald L Butac(74) *Attorney, Agent, or Firm* — Rowan TELS LLC(57) **CLAIM**

The ornamental design for a robot, as shown and described.

DESCRIPTION

FIG. 1 is a top, front, right perspective view of a robot showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a front elevation view of a robot, in an alternate position thereof;

FIG. 9 is a right-side elevation view of a robot, in an alternate position thereof;

FIG. 10 is another top, front, right perspective view of a robot, in an alternate position thereof;

FIG. 11 is another top, front, right perspective view of a robot, in another alternate position thereof;

FIG. 12 is a front elevation view of a robot, in an alternate position thereof;

FIG. 13 is a right-side elevation view of a robot, an alternate position thereof;

FIG. 14 is another top, front, right perspective view of a robot, in an alternate position thereof; and,

FIG. 15 right-side elevation view of a robot, in an alternate position thereof.

The broken lines show portions of a robot which form no part of the claimed design.
